DESIGN FOR A TEXTILE FABRIC

George J. Feinberg, Englewood, N. J.

Application September 20, 1945, Serial No. 122,217

Term of patent 7 years

(CL D92—1)

To all whom it may concern:

Be it known that I, George J. Feinberg, a citizen of the United States, residing in Englewood, in the county of Bergen, State of New Jersey, have invented a new, original, and ornamental Design for a Textile Fabric, of which the following is a specification, reference being had to the accompanying drawing, forming part thereof.

The figure is a plan view of a piece of textile fabric showing my new design.

I claim:

The ornamental design for a textile fabric, substantially as shown.

GEORGE J. FEINBERG.
